UNITED STATES PATENT OFFICE.

HUGH B. LOWDEN, OF DENVER, COLORADO.

DRYING APPARATUS.

1,377,896.

Specification of Letters Patent. Patented May 10, 1921.

Original application filed October 22, 1917, Serial No. 197,905. Divided and this application filed January 7, 1920. Serial No. 349,988.

To all whom it may concern:

Be it known that I, HUGH B. LOWDEN, a citizen of the United States, residing in the city of Denver, State of Colorado, have invented certain new and useful Improvements 5 in Drying Apparatus, of which the following is a specification.

This application is a division of an application filed by me in the United States 10 Patent Office on the 22d day of October, 1917, Serial No. 197,905.

My present invention relates to an apparatus for drying or partially eliminating moisture from materials, and is designed to afford simple, effective and economical 15 means for drying materials, particularly such as could not be handled satisfactorily in driers of preexisting types, or if so handled, would suffer serious dust losses or injury to 20 the quality of the product.

As an example of the class of material to which my present invention is especially adapted, I mention flotation concentrates, obtained in the treatment of ores. This 25 product is customarily dewatered on continuous revolving drum vacuum filters, but after such dewatering, still retains sufficient moisture to render it plastic, which occasions serious difficulty in subsequent treatment, 30 such, for example as the impossibility of so mixing it with other, usually dry, ingredients as to properly incorporate it in a suitable charge for sintering. Where the flotation concentrates from their nature, are preferably roasted directly, as in multiple hearth 35 roasting furnaces, their high moisture content reduces the capacity of the furnaces, and their cohesive and adhesive qualities cause them to interfere with the normal operation of the rabbling means, as also to ball 40 up and resist proper exposure to the air.

The difficulties above alluded to are new ones, in that they were practically non-existent prior to the advent of the flotation 45 process. Novel means were required to meet them and the invention herein described discloses a thoroughly satisfactory apparatus for overcoming them. However, my invention is equally well adapted to other products which have heretofore been difficult to 50 dry on a large scale.

I dry the product mentioned, or other material, by feeding it to a heated surface and operating upon it in such a manner that there 55 is no loss from dusting, no interference with

the operation by clogging, no possibility of undried material being discharged, and practically no loss of efficiency through heat insulation by part of the material operated upon remaining immediately upon the 60 heated surface and not being removed when dry. Furthermore, by thus drying upon a heated surface there is no contamination of the product by the smoke and gases of combustion, which is objectionable with certain 65 classes of material.

One or more of the above defects is present in all preexisting driers of which I am aware. Direct heat driers carry off a prohibitive amount of dust in operation, and 70 also permit the contamination of the material by the products of combustion. All revolving cylinder driers are subject to operating difficulties due to plastic material adhering to their interiors and to balling up of 75 the cohesive material. Drying upon hearths rabbled by chain dragged rabbles is attended by the discharge of undried material which has adhered to the rabbles; and, if the clogging is extensive, by the sweeping of all or a 80 large part of the material undried from the hearth. Drying upon hearths over which the material is advanced by so-called grasshopper conveyer mechanisms is of very low efficiency, due to material remaining upon 85 the hearth and not being removed owing to the arcuate paths described by such mechanisms, and to the fact that such mechanisms do not break up masses of adhesive material, but tend to ball it up and push or roll the 90 masses over the hearth.

The first of the latter two defects prevents efficient heat transference from the hearth to the material, and the second impedes the escape of moisture from the material into the atmosphere. 95

The operation of these machines differs essentially from that of my apparatus in that they do not include the distinct subdividing of cohesive masses of material, 100 whereas my machine effects the repeated cutting of such masses, thereby exposing fresh surfaces and preventing the material from baking in hard lumps from which moisture is very slowly eliminated. As a result of 105 this, satisfactory operations of all such methods is limited to granular materials having little or no cohesive and adhesive properties. This is commonly recognized, and such driers, owing largely to the absence 110

of definite break-up action in their methods of operation are generally regarded unsuitable for drying flotation concentrates, and, so far as I am aware, flotation concentrates 5 are not dried by any of them in practice.

For efficiently drying the class of materials referred to, I have found it necessary to move the material over the hearth by repeated short strokes, and to also cleave the 10 cohesive masses with such frequency that fresh surfaces are exposed for the escape of moisture and the material is not permitted to dry or bake in lumps.

In my improved apparatus I preferably 15 use a hearth surmounting a flue through which I pass the heated gases of combustion as from a fire-box, or waste heated gases from some other operation, if available, but this hearth is a representation of any drying 20 surface however heated, and in fact, my hearth may consist of a jacketed pan through which exhaust or live steam is passed, or of any surface heated by other means. Under certain conditions a muffle might be preferable 25 to a hearth, and such a muffle might be heated from without, air, or heated air or gases being forced or drawn through the interior of the muffle or not, or the only heat applied might be through the medium of 30 heated air or gases passed through the muffle.

The drying might be accomplished, either upon a hearth or within a muffle, by mere exposure to the atmosphere, without the application of heat, when, for example, the material 35 would be injured by an elevated temperature.

In describing my apparatus I shall confine myself to a hearth heated from beneath, as the operation in a muffle or upon any other 40 surface will be readily understood therefrom.

I feed the material upon the hearth at one end, and operate upon it by a large number of plows, or rabbles, which conveniently act simultaneously. I move this series of rabbles, which collectively I designate a rake, by 45 mechanical means, forward as closely to the hearth as practicable; I then raise them out of contact with the material on the hearth in a substantially vertical direction so that 50 there is no tendency of the rabbles to drag over or compress the material. I then move them backward out of contact with the material on the hearth, and next lower them into the material so that they cut into the masses 55 left by the preceding forward stroke. This is one cycle of the operation which proceeds continuously as long as power is applied, and it will be seen that there is no possibility of undried material being discharged, as any 60 masses which adhere to the rabbles will fall back upon the hearth at or near the point from which they are lifted.

I append hereto drawings illustrating my preferred form of apparatus, the various 65 parts being designated by reference charac-

ters, the same reference character indicating the same or corresponding part in the various figures.

In the drawing:

Figure 1 represents a transverse section 70 through the hearth, flue, rake and operating mechanism.

Fig. 2 is a longitudinal section on the line 2-2 of Figs. 1 and 3.

Fig. 3 is a plan of the operating mech- 75 anism.

Fig. 4 shows another mechanism for securing a suitable rectilinear motion in four directions.

Fig. 5 is a detail of my preferred hearth 80 construction.

Fig. 6 is a transverse sectional elevation of my rabbelling means embodied in a muffle.

Figs. 7 and 8 are details of the last named.

Figs. 9 to 12 inclusive are details of an at- 85 tachment to the rake.

Fig. 13 shows my preferred arrangement of the rabbles.

In Fig. 1, the hearth composed of cast iron plates, is shown at 1. These rest upon longitudinal side walls 2, with which they form a flue, through which heated gases, as from a fire-box, are passed for the purpose of heating the hearth. The bottom of this flue may be paved, as indicated at 3. The rake, 4, is 90 studded with plows or rabbles 5, and is adapted to operate in connection with the hearth. Piers 6 are shown supporting the rake operating mechanism.

In Fig. 2 the hearth is shown at 1, the rake 100 at 4, with its rabbles 5. At 7 are bearings fixed to the tops of the piers 6 of Fig. 1. 8 is a bar adapted to slide lengthwise in the bearings 7, 9 are blocks fixed upon the bar 8. 10 are bearings fixed upon the bar 8 so as to 105 move with it and receive the rock shafts 11. The rock shafts 11 carry arms 12 and 13, extending substantially at right angles to each other and forming in effect a bell crank. The arms 12 carry the rake at their free ends 110 by the uprights 14 and 14^a, and by the vertical oscillation of their free ends effect the raising and lowering of the rake.

At 15 is shown a shaft, the rotation of which operates the rake mechanism, through 115 the crank 16, which communicates a reciprocating motion to the connecting rod 17. The rod 17 is connected at its other end to a cross-head 18, which is adapted to reciprocate in suitable guides in the blocks 9. The reciprocation of the crosshead with respect to the blocks 9 is limited by the set screws 20.

The extent to which the crosshead can reciprocate in the blocks 9 is less than the stroke of the connecting rod 17, and after it has been moved to the limit fixed by the set screws 20, further motion of the connecting rod will cause the bar 8 to slide in its bearings 7. This effects the horizontal components of my rectangular motion.

The vertical components of my motion are effected by the connection of the crosshead with the arm 13, by the rod 21, which converts the reciprocating motion of the crosshead into an oscillating motion of the rock shaft.

The operation of the mechanism is therefore as follows:

Power is applied to rotate the shaft 15, which through the crank 16, causes the bar 17 to reciprocate. The first effect of this reciprocation, assuming it to be toward the left (in Fig. 2) is to draw the upper end of the arm 13 toward the left, thus depressing the arm 12 and forcing the rake down into the material on the hearth. This movement is interrupted by the set screw stop 20 after which the stroke moves the bar 8 with all its attached parts, including the rake, toward the left until the crank 16 reaches the dead center.

After passing the dead center, the connecting rod 17 will move toward the right, first sliding the crosshead in its guides and raising the rake until the crosshead engages the set screw, then pushing the rake toward the right in its upper plane of travel and out of contact with the material on the hearth. This completes one revolution of the shaft 30 or one cycle.

As above indicated, the set screws 20 control the extent of the vertical component of the rectangular path described by the rake. In practice, I allow ample lift, and use the excess to regulate the horizontal component. The set screw 20 at the left, in Fig. 2, should be so adjusted that the rake will operate as closely as possible to the hearth on the forward stroke. The set screw shown at the 40 right controls the height to which the rake is lifted, and an excess over what is really necessary is without effect on the operation. Therefore, this set screw is used to fix the length of the forward stroke, so that the 45 rabbles on rising leave the masses of material at the proper points for the rabbles on again descending to cut into and effectively subdivide them.

It will be understood that although I have 50 described my mechanism and its operation by reference to a single set of the essential elements, I in fact make use of more than one set.

Thus in Figs. 2 and 3 the rake has four 55 points of support, corresponding to which there are four bell cranks on two rock shafts. The bell cranks obviously should oscillate in unison, and this may be conveniently provided for by connecting the arms 13 by the 60 rods 22.

In practice, I counterbalance the rake by counterweights indicated at 23.

I preferably construct my rake of longitudinal members 24 to which transverse bars 65 25 are fixed at intervals. The transverse

bars bear the rabbles 5 which I make of sheet metal.

In the mechanism just described, the vertical components of the rectangular movement are not strictly vertical, that is straight 70 line movements, but through an arc of which the rock shaft is the center. However, the bell crank principle is exceedingly simple and convenient and I have found in practice that the slight departure from a true straight 75 line is wholly immaterial.

I show, in Fig. 4, means for obtaining a truly straight line rectangular motion, this figure including only the parts which would take the place of the bell crank of Fig. 2. 80

In said Fig. 4, 8 is the reciprocating bar, 24 is the longitudinal member of the rake, and 14^b is the rake upright. A vertical guide bar 26 is attached to the reciprocating bar, as by the set screw 27, and the rake upright is furnished with parts 28 encircling the guide bar which permit it to move only vertically on the guide bar. 29 is a toggle, connecting the rake upright with the bar and 21 is the connecting rod attached at the end 90 shown to the knee of the toggle, and at the other end to the crosshead. A pull on the rod 21 will raise the rake and a push will lower it.

Fig. 5 is a partial longitudinal section 95 through the hearth, showing how I form the pans which compose it. Expansion and contraction in a long hearth is considerable, and bolting the sections together would be unsatisfactory on that account. I make the individual sections of the hearth to lap, one over the other, as at 30, and I bevel the edges as at 31, so that any material which may have collected in the space between them will, upon further expansion due to higher 100 heating, be forced upward and out of the joint and prevent one section from tending to displace the adjoining one. 32 are strengthening ribs, and 33 is a lug in the center of each side of the hearth pan. This 105 lug 33, rests in a small anchor plate 34 (also shown in Fig. 1) which it fits snugly in a direction longitudinally of the hearth, but sufficiently loosely in a transverse direction to permit expansion to be accommodated for. Thus each individual hearth plate can expand or contract transversely by the lug sliding in the anchor plate, and longitudinally by the edge of one plate sliding upon the other, the lug 33 holding 110 the center of each plate and consequently the entire length of the hearth fixed.

Fig. 6 shows apparatus for conducting the operation in a muffle. In this, continuous walls 35 replace the piers (6 in Fig. 1), 115 and a hood 36 forms with the walls a muffle.

The hood of the muffle, I provide with slots 37, through which the rock shafts extend. The special features of these slots are shown in Figs. 7 and 8. Fig. 7 is a side 120 125 130

elevation of a small part of the hood, and Fig. 8 is a transverse section on the line A—A of Fig. 7.

To prevent excessive leakage through the slot I provide a cover plate 38 carried by the rock shaft which has a working fit in the boss 39. The plate is retained by the lugs 40, but is free to slide forward and backward with the rock shaft.

- 10 The material to be dried may be fed to the hearth automatically in the form of the discharge from a revolving drum filter, in which case it may conveniently fall to it over the apron plate 41 of Figs. 9, 10, 11 and 12.
- 15 Material in a certain physical condition will have a tendency to fall and remain upon the rake bars at this point, and I provide a deflector 42 attached to the rake by the hinge 43. This deflector is free to move within limits fixed by the length of stroke of the rake and the position of the stationary pins 44 and 45.

In Fig. 9 the rake is shown at the completion of the backward stroke, before it has been lowered. In this position the deflector rests upon the pin 45 and will catch any material which in its absence would fall upon the rake. Fig. 10 shows the rake after the lowering movement, the deflector still resting upon the same pin and shielding the rake.

As the rake moves forward, that is toward the right, the lower end of the deflector will be carried with it, and the upper end will ride upon pin 45 until the center of gravity of the deflector with its load passes to the right of pin 45, whereupon it will fall upon pin 44 and the jar it thereby receives will shake off adhering material. This position of the parts is represented in Fig. 11.

Fig. 12 shows the rake after completion of the rising movement and before the backward stroke has commenced. The deflector is still resting upon the pin 44 and will continue to do so until the hinge passes to the left of it, when it will fall upon pin 45, and at completion of the stroke be again in the position shown in Fig. 9.

In Fig. 13, I show a detail of my preferred rake construction. The figure is a plan of a small section of my rake, and shows the manner in which I dispose the rabbles 5 on the transverse rabble bars 25 to positively effect the subdividing or cleaving of the material being dried. Adjacent bars carry alternately right-hand and left-hand rabbles; thus, if those on the bars 25^a are designed right-hand, those on 25^b will be left hand.

60 The rabbles, moving forward, will each push along what material is in front of them, and when they are raised, will leave it in small masses upon the hearth. Now I so proportion the distance between the rabble bars and the length of the stroke

of the rake, that upon again entering the material they do not enter the spaces left by the previous stroke, but enter these masses and cleave them; the repetition of this action soon accomplishing a thorough subdivision 70 of the material.

If the conveying movement of the rake is assumed to be upward in the plane of the paper, in Fig. 13, and the rake is assumed to have completed the conveying stroke, it 75 will next rise, and after completing the return stroke, descend into the material, the rabbles on 25^a entering the piles of material left by the rabbles on 25^b, thereby cutting them open and exposing fresh surfaces. 80

In practice, more or less material, if adhesive, clings to the rabbles; but this does not interfere with the satisfactory operation of the machine, because owing to the action of the rake being a reciprocating one, the 85 material so attached to the rabbles will eventually fall back upon the hearth in substantially the same place it was lifted from, and cannot be discharged undried.

When operating upon adhesive material, 90 there is little or no actual plowing action at the feed end of the hearth, due to the obliquity of the rabbles, nor is this essential at that stage of the drying, the chopping up of the masses being there most important. 95 However, after the material has lost a portion of its original moisture, and has become thoroughly subdivided, the rabbles do then push it sidewise as well as forward and this action effectively exposes all parts of it to 100 the heat of the hearth and to the atmosphere. I attach the rabbles 5 adjustably, so that their angles with the rabble bars can be changed, and the rake caused to convey the material rapidly or slowly, as may be desired. 105

The rake, operating immediately above the hearth, is subjected to a higher temperature than the reciprocating bars 8 and to permit the unequal expansion of these parts, 110 I make a rigid attachment to but one end of the rake, that being shown at 14. Other supports I connect by links 14^a connected to both rake and arm 12. This adapts such link 14^a to lift and lower and causes the 115 reciprocation to be communicated to the rake by the rigid upright 14. This provision prevents unequal expansion from setting up strains and promotes smoothness of operation. It also eliminates vibration 120 which a long rake would be subjected to if rigidly connected at all points of support.

The operation of my method of drying is carried out by use of the herein described apparatus as follows:

Heat is continuously communicated to the hearth, and the material delivered upon it, preferably also continuously, as by allowing it to fall directly from the discharge of a drum filter. The feed end, in the drawings 130

forming part hereof, is the end remote from the driving mechanism.

Assuming the rake to have completed the backward or return stroke, it descends into the material, the rabbles cutting the lumps or ridges of material left by the rake upon rising for the return stroke. Forward movement of the rake now takes place closely to the surface of the hearth, each 5 rabbles pushing forward and sidewise the material in its path. The rake next rises and then returns to the backward limit of its stroke, moving in a plane above and out 10 of contact with the material on the hearth, 15 this completing one cycle.

The material being thus moved through but a small portion of the length of the hearth by one stroke of the rake, requires considerable time in passing over its entire 20 length and is subjected to the cleaving and plowing action of the rabbles repeated many times.

The time required for drying differs with the nature of the material and amount of 25 moisture in it, as well as with the extent to which the moisture must be eliminated. The time it will remain on the hearth can be regulated by the speed of revolution of the shaft 15 and by the angle at which the 30 rabbles are set. Thus the speed and the rate of feed being unchanged, a thin bed of material moving rapidly or a deep bed moving slowly may be maintained, depending upon whether the rabbles are slightly or steeply 35 inclined to the longitudinal axis of the hearth.

What I claim is:

1. In combination a drying surface, means for feeding material thereto in a layer or 40 stratum and means for cleaving it at a plurality of isolated points in a substantially vertical direction, pushing the cleaved portions lengthwise of the drying surface and again cleaving the material at points intermediate the previous cleavings.

2. In combination a hearth, means for delivering material thereto at one end, means for heating the hearth, and means for repeatedly cleaving the material in a substantially 50 vertical direction and advancing it through a small portion of the length of the hearth intermediate each cleaving.

3. In combination a material supporting surface, a slidable element mounted to reciprocate parallel to said surface a cross-head mounted to have a limited sliding motion relative to said slidable element, a rake, means connecting the rake and said slidable element for supporting the rake and raising 55 and lowering the same, and means connecting the cross-head with said raising and lowering means.

4. In combination a material supporting surface, a slidable element mounted to reciprocate parallel thereto, a cross-head 60

mounted to have a limited sliding motion relative to said slidable element, a bell crank lever pivotally supported on said slidable element, a connection from said cross head to one arm of said bell crank lever, and a 70 rake carrying member supported from the other arm of said lever.

5. In combination, a material supporting surface, a bar or rod mounted to have sliding movement parallel to said surface, a 75 cross-head mounted to have a limited sliding movement on said bar, a bell crank lever pivotally supported by said bar, an operating connection from one arm of said cross-head to one arm of said bell crank lever, and a 80 rake carrying element supported from the other arm of said bell crank lever.

6. In combination, a material supporting surface, a bar or rod mounted to have a sliding movement parallel to said surface, a 85 cross-head slidably supported by said bar, adjustable means for limiting the sliding movement of the cross-head on said bar, a bell crank lever pivotally mounted on said bar, a connection between said cross-head 90 and one arm of the bell crank lever, and a rake carrying element supported from the other arm of said bell crank lever.

7. In combination a material supporting surface, a bar or rod mounted to reciprocate parallel to said surface, guides rigidly carried by said bar, a cross-head having oppositely extending members slidably supported by said guides, adjustable stops carried by said guides coacting with said members to limit the sliding movement of the cross-head relative to said bar or rod, a bell crank lever pivotally mounted on said bar or rod, an operating connection between said cross head and one arm of said bell 100 crank lever, and a rake supporting element carried by the other arm of said bell crank lever.

8. In combination, a material supporting surface, a bar or rod mounted to reciprocate parallel thereto, opposed socket members carried by said bar or rod, a cross-head having oppositely extending parts slidably guided in said socket members, set screws threaded through the ends of said socket 110 members and adapted to contact with the ends of the cross-head parts to limit the movement of the cross-head relative to said bar, a bell crank lever pivotally carried by said bar or rod, operating means connecting the cross-head with one arm of the bell crank lever, and a rake supporting element 115 connected to the other arm of the bell crank lever.

9. In combination a material supporting 125 surface, a slidable element mounted to reciprocate parallel to said surface, a cross-head mounted to have a limited sliding movement relative to said element, a bell crank lever pivotally carried by said slid- 130

- able element, a connection from said cross-head to one arm of said bell crank lever, a rake supporting element carried by the other arm of said bell crank lever, and a counter-
5 weight tending to rock said bell crank in opposition to the weight of the rake.
10. In combination a material supporting surface, a rod or bar mounted to reciprocate parallel to said surface, a pair of bell crank levers pivotally supported by said bar, a cross-head mounted to have a limited reciprocating movement relative to said bar with means for operating it, each of said bell cranks having one arm extending substantially vertically and the other arm substantially horizontally, means connecting said cross-head with the vertically extending arms of the bell crank levers and a rake carrying frame supported from the horizontally extending arms of said bell crank levers.
11. In combination a material supporting surface, a rod or bar mounted to reciprocate parallel to said surface, a pair of bell crank levers pivotally supported by said bar, a cross-head mounted to have a limited reciprocating movement relative to said bar with means for operating it, each of said bell cranks having one arm extending substantially vertically and the other arm substantially horizontally, means connecting said cross-head with the vertically extending arms of the bell crank levers, a rake carrying frame, a rigid post member carried by one part of said frame and pivotally connected to the horizontal arm of one bell crank lever, and flexible means connecting another part of said frame with the horizontal arm of the other bell crank lever.
12. In a conveying rake supported at a plurality of points, rigidly attached means at one point for transmitting both vertical and horizontal movements thereto, and flexi-
bly attached means at another point for transmitting vertical movement without interfering with the horizontal movement.
13. In a conveying rake supported at a plurality of points in its length, rigidly attached members at one point for transmitting both vertical and horizontal movement, flexibly attached members at the other point or points for transmitting vertical movement, and means, adjustable as to length of the horizontal movement, for operating.
14. A drying surface within a muffle, a rake in operative relation thereto, rake operating means outside the muffle, and movable means for sealing the opening in the muffle through which the moving parts extend against passage in or out of air, vapor or gas.
15. A muffle having a drying surface within the same, a rake in operative relation to said surface, rake operating means outside of the muffle for moving the rake lengthwise of the muffle, said muffle having longitudinally elongated openings in its walls, said rake operating means having parts extending through the openings and connected with the rakes, and slidtable plates covering said openings.
16. A drying surface within a muffle, a rake in operative relation thereto, means for imparting horizontal and vertical motion to the rake in a substantially rectangular closed path, and means outside the muffle for adjusting the length of stroke of the rake.
17. In combination a hearth, a rake with means for imparting a reciprocating motion thereto, and a deflector carried by said rake adapted to receive material falling from above and deliver it to the hearth.
- In testimony whereof, I affix my signature.

HUGH B. LOWDEN.
